SELF-THREADING NEEDLE

Leighton Homer Surbeck, New York, N. Y.

Application January 14, 1952, Serial No. 266,292

8 Claims. (Cl. 223—102)

1

This invention relates to sewing needles, and more particularly to a self-threading needle, i. e., one in which the needle itself is so formed as to facilitate the threading thereof, eliminating much of the difficulty, ocular strain, and general inconvenience occasioned by the necessity of projecting a thread through the eye of a needle in the usual manner.

It is a general object of the invention to provide a sewing needle of generally conventional form, comprising a slender, generally cylindrical shaft provided with a sharp point at one end, the other end being blunt and being provided with an eye to receive the thread, the blunt or "head" end of the needle being so formed as to facilitate alignment of the end of a thread with the eye of the needle, as well as the actual projection of the thread end through said eye.

More specifically, it is an object of the invention to provide a needle of the class described, that wall of the eye nearest the head or blunt end of the needle being inclined relative to the axis of the needle, so that the said wall intersects the peripheral surface of the needle at an acute angle, so that the end of a thread, when in engagement with said end wall of the eye, will be guided through the eye to the other side of the needle.

A further object is the provision of a needle formed as described in the preceding paragraph and provided also with a notch or groove in that portion of the needle between the eye and the blunt end, said groove terminating at or adjacent the said point of intersection of the end wall of the eye and the peripheral surface of the needle, the purpose of said notch or groove being to facilitate initial engagement of a thread in such manner that, by subsequent relative longitudinal movements of the thread and needle, the thread end may first be brought into position within the eye of the needle and in line with the aforesaid acute intersection, and then caused to progress upwardly along the said inclined wall so as to be projected through the eye.

A still further object is the provision of a needle such as described in the preceding paragraph, and provided further with a longitudinal groove extending from the eye toward the pointed end of the needle, said groove being of sufficient depth to accommodate a thread of the size suited for use with the particular needle, so that when the thread is in position for the commencement of the threading movement, the entire thickness of the thread may be encom-

2

passed within the cylindrical outline of the needle, whereby the thread end will necessarily be brought into engagement with the aforesaid inclined wall when the needle and thread are moved relative to each other.

Other and further objects, features and advantages will be apparent from the description which follows, read in connection with the accompanying drawings in which

Figure 1 is an elevational view of a needle formed according to the invention, looking from that side on which the head end wall of the eye extends nearest to the blunt end of the needle;

Figure 2 is a view similar to Figure 1 but taken at 90° in the rotation of the needle about its own axis, the head portion of the needle being shown in axial section;

Figures 3, 4 and 5 are transverse sections on lines 3—3, 4—4 and 5—5, respectively, of Figure 2;

Figures 6, 7 and 8 are enlarged views similar to Figure 2 showing successive relative positions of the needle and a thread in the process of threading the needle;

Figures 9 and 10 are similar to Figures 6, 7 and 8 but showing a loop of thread being projected through the eye, rather than a thread end;

Figures 11 and 12 are similar to Figures 9 and 10, but illustrating the use of a modified form of needle; and

Figures 13 and 14 are similar views illustrating the use of another modified form of needle.

In order to facilitate an understanding of the invention, reference is made to the embodiments thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

Referring now to Figures 1—8 of the drawings, it will be seen that the needle designated generally by the reference character 10 is, in outline, of conventional shape comprising an elongated shaft, pointed at one end and blunt at the other, and provided with an opening or eye 11 extending through the needle near its blunt end. The formation of the eye 11, in the present instance, is, however, somewhat different from that of a conventional needle. Thus, as

best seen in Figure 2 and Figures 6-8, the eye 11 is formed with its axis inclined to the longitudinal axis of the needle, that is to say, its end walls 12 and 13, which are, of course, transversely curved as seen in Figure 1, are inclined to the axis of the needle so that, for example, head end wall 12 intersects the peripheral surface of the needle in an acute angle at one end of the wall, i. e., at point 14 and an obtuse angle at the opposite end of the wall, point 15. The end wall 13 nearest the point of the needle is preferably, though not necessarily, similarly inclined.

The short portion lying between the eye 11 and the blunt end of the needle is provided with a longitudinal groove 16 opening in the blunt end of the needle and extending, with decreasing depth, to substantially the point 14 at which the end wall 12 of the eye intersects at an acute angle with the peripheral surface of the needle. The greatest depth of the groove 16, at the blunt extremity of the needle, may exceed one-half the diameter of the needle, but need not necessarily do so. It should, however, be of a depth somewhat in excess of the thickness of the thread to be used with the needle so that, as an initial step in the threading of the needle an end length of thread may be imprisoned between the walls of the groove 16 and the surface of a finger of the person using the needle as seen in Figure 6.

At the opposite or "point" end of the eye there is formed a second longitudinal groove 17 which extends toward the point of the needle for a short distance, for example for a longitudinal distance corresponding generally to the longitudinal dimension of the eye 11. The groove 17 has a depth approximating the thickness of the thread to be used with the needle, the purpose of the groove 17 being to allow a length of the thread to lie wholly within the outline of the cylindrical surface of the needle when imprisoned in this position by contact with a finger of the user, as seen for example in Figures 7 and 8. The groove 17, of course, opens into the eye 11 at a point opposite, i. e., in alignment with, the point 14 of acute intersection.

From the foregoing description it is believed that the manner of using the needle of Figures 1-8 will be easily understood. As seen in Figures 7, 8 and 9, the first operation in threading the needle is to place the groove 16 at the blunt end of the needle over the thread 18 at a point near an end of the latter, meanwhile pressing the thread upwardly with the finger so as to maintain it in the groove 16. The thread being gripped by the user so that it cannot have longitudinal movement relative to the user's finger, a relative movement is then brought about between the needle and the thread as by moving the needle to the left or the finger to the right to the position seen in Figure 7. In the course of this movement a length of the thread is brought into the groove 17 and is held there by engagement with the finger, the end portion of the thread being thus brought into the eye 11 with its extreme end in alignment with the point 14, at the lower end of the inclined wall 12 of the eye. A reverse relative movement of the finger and needle is then produced by moving the needle to the right or the finger to the left, so that the extreme end 19 of the thread is engaged by the inclined wall 12 and is guided upwardly through the eye 11, when it may be grasped and the thread pulled through the eye to the desired extent.

Instead of the operation just described, the

needle of Figures 1-8 may be threaded by projecting a loop of the thread, instead of an end thereof, through the eye of the needle, as illustrated in Figures 9 and 10. Thus, if the groove 16 is placed over a portion of the thread at a greater distance from its end than is contemplated in the preceding explanation, and the needle is then manipulated relative to the finger as described above, the thread will be caught at the point 14 of intersection of the inclined wall 12 and the periphery of the needle, and continuing movement of the needle toward the right, relative to the finger of the user will cause the formation of a loop 20 in the thread, which loop will be projected through the eye of the needle. The only limitation on this manner of threading the needle is that the eye must be of a certain minimum length depending upon the flexibility of the thread with which it is used or, in other words, the thread must be sufficiently flexible to permit the formation of a loop of such dimensions as may be projected through the eye.

Figures 11 and 12 illustrate a similar operation but a somewhat modified form of needle. In this modification, the wall 13' at the "point" end of the eye is inclined oppositely to the inclination of the wall 12 so that it intersects the periphery of the needle at an acute angle at a point 21 opposite the point 14. The longitudinal groove 17', therefore, does not open into the eye of the needle, as in the form of needle illustrated in Figures 1-10, but terminates just short of the eye, as shown.

Using the form of needle seen in Figures 11 and 12, a loop of thread may be projected through the needle by alternate movements of the needle in opposite directions, relative to the user's finger, the thread being frictionally engaged alternately by the points 14 and 21, to cause the formation of a loop 22 as seen in Figure 12. Alternatively, a thread end may be projected through the eye in the same manner as described in connection with Figures 6-8. For projecting a loop through the eye, the acute angles 14 and 21 could, of course, be right angles as well, but for projecting a thread end through the eye, as described in connection with Figures 6-8, inclined walls 12 and 13' are preferred.

In Figures 13 and 14, the wall 13' at the "point" end of the eye is inclined as described in connection with Figures 11 and 12, but the wall 12' at the other end of the eye is similarly, rather than oppositely, inclined and intersects the groove 16 at a point lying inwardly of the periphery of the needle, or in other words, the groove 16 opens into the eye of the needle. In this modification the groove 17 or 17' of the previously described forms is omitted. This form of needle may be threaded simply by placing the groove 16 over the end portion of a thread and moving the needle to the left as seen in Figures 13 and 14, whereby the thread end is caused to engage the inclined wall 13' and is thus projected through the eye.

Having thus described the invention, what is claimed as new and desired to be secured by Letters Patent is:

1. Self-threading sewing needle comprising a generally cylindrical shaft having an elongated, pointed portion of conventional form and an integral blunt head portion, said head portion being formed with an elongated eye therethrough, the wall at one end of said eye being inclined relative to the axis of said shaft, one end of said end wall intersecting the peripheral surface of

said shaft at an acute angle, the head end of said shaft being formed with a longitudinal groove extending from the blunt extremity thereof substantially to the said eye, the said groove lying on the same side of said needle as the said acute angle, the depth and width of said groove at its intersection with the blunt extremity of the needle being not less in extent than the width of said eye.

2. Needle according to claim 1, said shaft being formed with a second longitudinal groove extending substantially from the point end of said eye toward the pointed end of the needle, said second groove being in longitudinal alignment with the said first groove.

3. Needle according to claim 1, the wall at the head end of the eye being inclined, said shaft being formed with a second longitudinal groove extending from the point end of said eye toward the pointed end of the needle, said groove opening into said eye at a point in longitudinal alignment with the said acute intersection.

4. Self-threading sewing needle comprising a generally cylindrical shaft having an elongated, pointed portion of conventional form and an integral blunt head portion, said head portion being formed with an elongated eye therethrough, the wall at one end of said eye being inclined relative to the axis of said shaft, one end of said end wall intersecting the peripheral surface of said shaft at an acute angle, the head end of said shaft being formed with a longitudinal groove extending from the blunt extremity thereof substantially to the said eye, the said groove lying on the same side of said needle as the said acute angle, the depth and width of said groove at its intersection with the blunt extremity of the needle being not less in extent than the width of said eye, said shaft being formed with a second longitudinal groove extending substantially from the point end of said eye toward the pointed end of the needle, said second groove being in longitudinal alignment with the said first groove.

5. Needle according to claim 1, the other end wall of said eye being oppositely inclined to intersect the peripheral surface of said shaft at an acute angle at a point opposite said first acute angle intersection.

6. Needle according to claim 1, the said inclined wall being the wall at that end of the eye nearest the point of the needle, and said longitudinal groove opening into said eye at a point opposite said acute angle intersection.

7. Self-threading sewing needle comprising a generally cylindrical shaft having an elongated, pointed portion of conventional form and an integral blunt head portion, said head portion being formed with an elongated eye therethrough, the head end of said shaft being formed with a longitudinal groove extending from the blunt extremity thereof substantially to the said eye, the depth and width of said groove at its intersection with the blunt extremity of the needle being not less in extent than the width of said eye, the plane containing the longitudinal axis of said groove and the longitudinal axis of the needle being coincident with a plane extending through said eye and containing said axis of said needle.

8. Self-threading sewing needle comprising a generally cylindrical shaft having an elongated, pointed portion of conventional form and an integral head portion having a blunt end, said head portion being formed with an elongated eye therethrough, the wall at the head end of the eye being continuous and being inclined throughout its length relative to the axis of said shaft, one end of said end wall intersecting the peripheral surface of said shaft at an acute angle, said shaft being formed with a longitudinal groove extending from the point end of said eye toward the pointed end of the needle, said groove opening into said eye at a point in longitudinal alignment with the said acute intersection, said end wall extending from said acute intersection toward the blunt end of the shaft.
